UNITED STATES PATENT OFFICE.

KENNETH F. MIDDOUR, OF DES MOINES, IOWA.

ASH PIT.

Application filed February 10, 1928. Serial No. 253,344.

The object of my invention is to provide an ash pit structure of the kind used with furnaces of simple, durable and inexpensive construction.

5 More particularly, it is my object to provide in my present invention an ash pit having side wings serving to direct ashes into the pan, which side wings are of novel structure and are adapted to be quickly and easily 10 mounted on or detached from the ash pit.

A further purpose is to provide the combination of an ash pit adapted to serve practically with a removable pan, having guide devices and a third pan.

15 Generally, it is my purpose to provide an ash pit and a removable pan of novel construction and cooperating parts for affording means whereby ashes may be removed from a furnace pit with a minimum of inconvenience and labor.

20 With these and other objects in view, my invention consists in the construction, arrangement and combination of the various parts of my ash pit whereby the objects contemplated are attained, as hereinafter more 25 fully set forth, pointed out in my claims, and illustrated in the accompanying drawings, in which:

Figure 1 shows a top or plan view of an 30 ash pit and pans embodying my invention.

Figure 2 is a detail, sectional view taken on the line 2—2 of Figure 1, the ash pit and pans being installed in a furnace ash pit shown in section.

35 Figure 3 is a detail, sectional view taken on the line 3—3 of Figure 2, parts of the furnace being shown in section; and

Figure 4 is a perspective view of one of the removable side wings.

40 It is well known that ordinarily ashes must be removed from the ordinary furnaces in residences and the like by means of a shovel. It is difficult to keep the pit in the furnace clean and considerable labor is involved. The 45 shoveling of the ashes raises a dust, some of which always gets into other parts of the residence.

My improved ash pit comprises what may be called an ash pit adapted to be mounted 50 in the pit of a furnace and is of peculiar structure with removable side wings therefor, and a removable clean out pan adapted to slide into and out of the ash pit and a second pan, which is the ash container or 55 ash pan.

In the accompanying drawings, I have for

the purposes of illustrating the environment of my ash pit and pans shown a portion of a furnace indicated generally at A, having the ash pit B with the side walls 10 and bottom 12, the rear wall 14 and pit door 16.

60 My invention includes what may be called an ash pit C, having vertical side walls 18 and a bottom 20. The front of the ash pit C is open and the side walls at the front end 65 are slightly flared as at 18^a. The bottom 20 may be rounded or otherwise shaped at the rear and can fit the rear wall of the pit B.

70 The upper parts of the side walls 18 are connected at their rear ends by a brace strap or bar 22, which in the case of an ash pit, the rear end of which is curved, is also curved as shown in Figure 1.

75 It will be understood that if the rear end of the pit was made without a curve, the rear ends of the various ash pits herein described would be accordingly shaped.

80 The side walls 18 are preferably connected near the front end of the ash pit C at their upper edges by means of a cross bar 24 (see Figures 1 and 3). The ash pit C is intended to remain in the pit after its installation, and the flaring ends 18^a may be bolted to the furnace if desired.

85 Where the ash pit C is used, it is desirous that the ashes be guided into it by inclined side wings or other means serving the function of a chute.

90 I have in the present instance provided for the ash pit C a pair of side wings 26, one of which is shown in perspective in Figure 4, as viewed from the under side.

95 The upper edges of side wings are cut to shape so as to come into contact with the sides of the original furnace ash pit and for the different makes of furnaces the upper side of the side wings 26 are necessarily different.

100 It is desirous that the side wings 26 should rest in position above the respective side walls 18 overhanging the side walls laterally in both directions, so as to guide the ashes into the ash pan members.

105 Because the ash pit C is intended to remain permanently in the pit or to take the place of the pit, if no pit is employed, it is ordinarily too wide, when equipped with the wings, to slip through the opening for the door 16.

110 For purposes of installation, particularly in a furnace already built, it is desirable that the side wings should be detachable and should be easily assembled on the ash pit C.

For this purpose, each side wing is provided on what is its under side, when installed, with a pair of hanger brackets 30, which brackets are inclined away from the side wings at an angle of about forty-five degrees from the bases on the side wings.

At the forward end of each side wing is a slot 32, at the upper edge of which is a tongue 34 inclined similarly to the brackets 10 30.

After the ash pit C has been placed in the furnace pit, the side wings 26 are inserted through the door, and are set in position on the side walls 18 thereof with the brackets 30 15 and tongue 34 overhanging the outer parts of the side walls as shown in Figure 2. The side wings thus serve as chute members for the ash pit C.

The ash pit C is necessary in order to facilitate the proper use of the other pans, which 20 will now be described.

Received in the ash pit C is a clean out pan D, having a bottom 36, side walls 38 slightly flared at their forward end, as at 40, and an 25 inner end wall 42. The clean out pan D is not so high as the ash pit C and slides into the ash pit C and may be drawn out by inserting any suitable tool into one of the holes 44 in the flared ends 40.

On the inner faces of the walls 18 just above the side walls 38 of the pan D are strips 46, which are inclined inwardly and downwardly from the walls 18 above the side walls 38 of the clean out pan D in such manner as to cause 35 all dropping ashes to drop into the clean out pan D and also to serve as guide members for the second pan E.

The clean out pan D is provided in its bottom with a series of longitudinally arranged 40 ribs 48 upon which the pan E may slide.

The pan E has a bottom 50, side walls 52, a front wall 54 and a rear wall 56. On the outer sides of the front and rear walls are handles 58. The side walls 52 are flared outwardly, so 45 that they may be guided between the strips 46 and will still be overhung by the wings 26.

In the actual use of my improved ash pit, the ash pit C is installed in the furnace beneath the fire box, preferably for permanent 50 placing.

The clean out pan D is placed in position, and the pan E is then shoved into place.

Ordinarily, the ashes will drop into the pan E, which may be pulled out and the contents 55 emptied in any suitable way with a minimum of handling and without raising dust, as is necessary when a shovel is employed.

If some ashes drop into the clean out pan D, the guide strips 46 and the ribs 48 will hold 60 the pan E spaced from the side walls of the other pans and above the bottom of the pan D, so that the ashes in the cleanout pan D will not seriously impede the movements of the pan E.

65 At longer intervals, the clean out pan D

may be withdrawn and emptied, but ordinarily, it is not necessary to empty it, except at infrequent intervals.

The clean out pan D may be entirely dispensed with or may be made integral with the 70 ash pit C.

A device of this kind saves a great deal of labor and inconvenience in handling the ashes of a furnace in a residence or other building.

Changes may be made in the details of the 75 construction and arrangement of the parts and of the number of units employed in my pit, and it is my purpose to cover by my claims, any modified forms of structure or use of mechanical equivalents, which may be reasonably included within their scope. For example if the pit C is built in originally as a 80 part of a furnace, the braces 22 and 24 may be eliminated.

I claim as my invention:

1. In a device of the class described, an ash 85 pit open at one end, detachable inclined side wings having holding cleats above their lower edges and below their horizontal centers of gravity inclined downwardly and away from such wings for engaging over the upper edges of the sides of the pit and supporting said wings in inclined positions overhanging the sides of the pit inwardly and outwardly.

2. In a device of the class described, an ash 90 pit open at one end, detachable side wings having holding cleats above their lower edges and below their horizontal centers of gravity inclined downwardly and away from such wings for engaging over the upper edges of the sides of the pit and supporting said wings in inclined positions overhanging the sides of the pit inwardly and outwardly, said pit and wings having coating parts for holding them against relative longitudinal movement.

3. In a device of the class described, an ash 95 pit open at one end, detachable side wings having holding cleats above their lower edges and below their horizontal centers of gravity inclined downwardly and away from such wings for engaging over the upper edges of the sides of the pit and supporting said wings in inclined positions overhanging the sides of the pit inwardly and outwardly, said pit having a cross bar and said wings being provided with notches for receiving the cross bar for preventing lengthwise movement of the wings.

4. In a device of the class described, an ash 100 pit having guide strips on each side on its inside spaced above its bottom, a clean out pan received in said pit having its sides overhung by said guide strips, and provided in its bottom with longitudinal ribs, and a second pan received in the clean out pan.

5. In a device of the class described, an ash 105 pit having guide strips on each side on its inside spaced above its bottom, a clean out pan received in said pit having its sides

overhung by said guide strips, and provided in its bottom with longitudinal ribs, and a second pan received in the clean out pan, said pit being provided with inclined side 5 wings overhanging its sides.

6. In a device of the class described, an ash pit having guide strips on each side on its inside spaced above its bottom, a clean out pan received in said pit having its sides 10 overhung by said guide strips, and provided in its bottom with longitudinal ribs, and a second pan received in the clean out pan, said pit being provided with inclined side wings 15 overhanging its sides, said side wings being readily detachable.

7. In a device of the class described, an ash pit open at one end, detachable side wings having holding cleats above their lower edges and below their horizontal centers 20 of gravity inclined downwardly and away from such wings for engaging over the upper edges of the sides of the pit and supporting said wings in inclined positions overhanging the sides of the pit inwardly and outwardly, 25 said pit having along its sides on its inside above its bottom inwardly inclined guide strips.

8. In a device of the class described, an ash pit open at one end, detachable side 30 wings having holding cleats above their lower edges and below their horizontal centers of gravity inclined downwardly and away from such wings for engaging over the upper edges of the sides of the pit and supporting said wings in inclined positions overhanging the sides of the pit inwardly and outwardly, 35 said pit having along its sides on its inside above its bottom inwardly inclined guide strips, a removable clean out 40 pan received in said pit adapted to be guided by said strips and being provided with upwardly and outwardly flaring sides overhung by said side wings.

9. In a structure of the class described, a 45 pit open at one end having overhanging side wings and being provided in its bottom with longitudinal ribs and with longitudinal guide strips at its sides, and a pan slidable on said ribs, said pan having flaring side 50 walls whereby the upper edges of the pan overhang the guide strips and underlie the wings.

10. In a structure of the class described, a 55 pit open at one end having overhanging side wings at the upper edges of its sides and provided below said wings with inwardly inclined guide strips, a clean out pan received in said pit below said guide strips having longitudinal ribs on its bottom, a second 60 pan received slidably in said clean out pan and projecting thereabove and adapted to slide between said side strips having flared side walls overhung by said wings.

11. In a device of the class described, an 65 ash pit open at one end, detachable side

wings having holding cleats above their lower edges and below their horizontal centers of gravity inclined downwardly and away from such wings for engaging over the upper edges of the sides of the pit and 70 supporting said wings in inclined positions overhanging the sides of the pit inwardly and outwardly, said pit having a cross bar and said wings being provided with notches for receiving the cross bar for preventing 75 lengthwise movement of the wings, horizontal guide strips on the inside of the ash pit at the sides thereof.

12. In a device of the class described, an ash pit open at one end, detachable side 80 wings having holding cleats above their lower edges and below their horizontal centers of gravity inclined downwardly and away from such wings for engaging over the upper edges of the sides of the pit and supporting 85 said wings in inclined positions overhanging the sides of the pit inwardly and outwardly, said pit having a cross bar and said wings being provided with notches for receiving the cross bar for preventing lengthwise movement of the wings, horizontal guide strips on the inside of the ash pit at 90 the sides thereof, and a clean-out pan removably received in said pit with its sides below the guide strips.

13. In a device of the class described, an ash pit open at one end, detachable side wings having holding cleats above their lower edges and below their horizontal centers of gravity inclined downwardly and away from such wings for engaging over the upper edges of the sides of the pit and supporting 100 said wings in inclined positions overhanging the sides of the pit inwardly and outwardly, said pit having a cross bar and said wings being provided with notches for receiving the cross bar for preventing lengthwise movement of the wings, horizontal guide strips on the inside of the ash pit at the sides 105 thereof, and a clean-out pan having its sides below said overhanging wings.

14. In a device of the class described, an ash pit open at one end, detachable side wings having holding cleats above their lower edges and below their horizontal centers of gravity 110 inclined downwardly and away from such wings for engaging over the upper edges of the sides of the pit and supporting said wings in inclined positions overhanging the sides of the pit inwardly and outwardly, said pit having a cross bar and said wings being provided with notches for receiving the cross bar for preventing lengthwise movement of the wings, horizontal guide strips on the inside of the ash pit at the sides thereof, a clean-out pan with its side edges below said 115 guide strips when assembled, and a second pan slidably received in the clean-out pan.

15. In a device of the class described, an ash pit open at one end, detachable side wings 120

having holding cleats above their lower edges and below their horizontal centers of gravity inclined downwardly and away from such wings for engaging over the upper edges of the sides of the pit and supporting said wings in inclined positions overhanging the sides of the pit inwardly and outwardly, said pit having along its sides on its inside above its bottom inwardly inclined guide strips, and a clean-out pan having its side walls under the guide strips when in place.

16. In a device of the class described, an ash pit, detachable inclined side wings supported on and overhanging said pit, said pit having longitudinal guide strips on the insides of its side walls, and a clean-out pan in said pit with its side walls under said guide strips.

17. In a device of the class described, an ash pit, detachable inclined side wings supported on and overhanging said pit, said pit having longitudinal guide strips on the insides of its side walls, a clean-cut pan in said pit with

its side walls under said guide strips, and a second pan removably received in the clean-out pan.

18. In a device of the class described, an ash pit, detachable inclined side wings supported on and overhanging said pit, said pit having longitudinal guide strips on the insides of its side walls, a clean-out pan in said pit with its side walls under said guide strips, and a second pan removably received in the clean-out pan, having flared sides for cooperating with the guide strips, so that its upper edges underlie the inner edges of the inclined side wings.

19. In a device of the class described, the combination of an ash pit having on the inner faces of its sides longitudinal guide strips, a clean-out pan in said ash pit with its side edges underlying said guide strips, and a second pan detachably received in said clean-out pan.

Des Moines, Iowa, January 3, 1928.

KENNETH F. MIDDOUR.
